Inventor:
John L. Martin

UNITED STATES PATENT OFFICE.

JOHN L. MARTIN, OF BUFFALO, NEW YORK.

SWING.

Application filed August 12, 1921. Serial No. 491,838.

To all whom it may concern:

Be it known that I, JOHN L. MARTIN, a citizen of the United States, residing at Buffalo, in the county of Erie and State of New York, have invented a new and useful Swing, of which the following is a specification.

My invention has no relation to any previous structure of record. Heretofore swing structures were based on the principle of suspension having members hung to swing dependingly from pivots or other bearings supported overhead. Overhead suspension requires large framework unsuited to limited space; and all ceiling or overhead attachments in a house or on a porch are either impracticable or undesirable.

The objects of my invention are, first, to develop rocking or swinging motion in a structure supported by a suitable base and independent of overhead suspension members; second, to provide convenient manual operating means for the occupants of the swing; third, to utilize resilient means or members tending to counteract the action of gravity, and thus largely to lessen the fatigue of operating the swing and to check the oscillation to set limits and to enhance pleasure by traveling on yielding or spring cushion supports; fourth, to effect economy of space when the swing is at rest; fifth, to make the swing movable on rollers when used in a house or on any floor; sixth, to provide adjustable seats; seventh, to provide a container for ballast to promote anchorage to a floor without any fastening thereto; eighth, to combine the use of transverse connecting braces with those of handle bars, ladder rungs, and foot rests as needed; ninth, to embody the principles of my invention in a structure with such modifications and additions as to adapt it to any suitable place, to all ages of persons, with one or more seats, and with or without a foot platform; and tenth, to effect economy in materials in attaining all these objects.

In my swing I employ a new basic principle, the opposite of suspension, whereby swinging motion is generated on a base for support, as though ordinary swing hangers and their bearings were reversed end for end to rock on a base. Motion is developed in a vaulting curve,—that is, with curves turned downward; whereas, the principle in a suspension swing develops curves turned upward.

My invention consists, first, in a base support with erect legs or levers fulcrumed to turn or to rock on the base and adapted to swing an elevated carrier and an accompanying foot platform to and fro. It consists, second, in transverse bars or rungs connecting the legs or levers in pairs to serve as braces; handle bars, ladder rungs, and foot rests as desired. It consists, third, in hanging to swing on transverse bearings carried by the legs or levers intermediate to their terminals, a carrier serving to connect the legs or levers, serving as a support for seats, and serving as an unyielding support to obtain reaction on the levers when manual pressure is applied forwardly on the handle bars by the occupants of the seats. It consists, fourth, in a foot platform hung in a manner similar to the carrier, below the same, and serving besides a foot support for an unyielding support to obtain reaction on the levers when manual force is applied on the handle bars rearwardly. It consists, fifth, in resilient means or members mounted and interposed in such manner that the action of gravity on the carrier and the load thereon may be opposed and gradually overcome. It consists, sixth, in a rolling brace for each pair of legs or levers mounted at the head terminals on bearings carried by the levers, mounted at the foot terminals on rollers, serving as intermittent partial supports of the legs or levers in lieu of an ample base support, serving to make practical a contracted base where room is limited, serving as a support and a medium for a resilient member to oppose the action of gravity upon the carrier and the load thereon, and serving as trucks for moving the swing. It consists, seventh, in a container for ballast built as part of the base to promote anchorage or stability in the swing.

In the accompanying drawings Figure 1, is a side elevation of my swing at rest with a position in motion partially indicated; Fig. 2, is an end elevation of the same closed; Fig. 3, is a view showing the manner of mounting a double torsion spring on one of the supporting rods on the framed base should I wish to use it in lieu of an extension spring; Fig. 4, is an end view of the same; Fig. 5, is a side elevation of a modified or enlarged framed base suited for use on a lawn where ample room is available, and showing another structure on which to mount extension springs to effect the same

results obtained and shown in Fig. 1; Fig. 6, is a vertical section of the same on the line A—B, and showing the manner of mounting and connecting the springs with 5 the legs or levers; and Fig. 7, is a view of a lever having a handle terminal.

The longitudinal sills 1, provided with beveled anti-pinch blocks 2, at their terminals, having mounted at their terminals the 10 transverse bearing rods 3, connected by the spaced transverse rounds or rungs 4, to the under sides of which is attached the base board 5, the erect truncated side boards 6, secured to the outer face of each of the sills, 15 the sloping transverse end boards 7, secured to the side boards, and the cover board 8, having the retaining cleats 9, secured to its under face adjacent to the side boards, and having engagement with the side boards by 20 means of the cotter pin 10, constitute the framed base of the swing.

On each of the transverse rods 3, and outside of the framed base, are mounted to rock the foot terminals of a pair of legs or 25 levers 11, spaced apart, braced, and connected by the transverse rounds or rungs 12, on their lower portions, and by similar rungs 13, on their upper portions; which latter also serve as handle bars. On the pivots 14, on 30 each pair of levers is hung to swing a light frame comprising two side bars 15, connected by a handle bar 16, serving as a grip for a baby or child unable to propel the swing while an older child is propelling the same. 35 One of these frames appears in broken lines swung outward and upward in Fig. 1, and the turns 17, serve to confine them in normal position.

In position parallel with the sills of the 40 base, intermediate to the terminals of the levers, and longitudinally connecting them with its terminals, there is hung to swing on the pivots 18, carried by the levers on their outer faces, the carrier, which comprises the bars 19, spaced apart, braced, and connected by the transverse rounds 20, carrying centrally the transverse rod 21, and provided at its terminals with the beveled anti-pinch blocks 22. On the carrier are mounted centrally 45 two adjustable seats each facing a set of said handle bars and in opposite directions, each to each. Each seat comprises two longitudinal bars 23, each having a hook recess 24, formed in the under edge at the rear terminal for engagement with the rod 21, connected transversely by a plurality of slats 25, but unequally spaced to avoid interference, each having secured to their rear under edges the vertical spacing blocks 26, having the recesses 24, and rotatable on the pivot screw 27, and having secured to the forward under edges the vertically spacing blocks 28, rotatable on the pivot screw 29. In Fig. 2, 50 only one seat in low adjustment appears, the 65 re-enforcing cleats 30, attached to the inner

faces of the levers to support the pivots 18, partially obstructing the view of the blocks 28. The rounds 20, serve as supports for the forward parts of the seats. By means of the blocks 26, and 28, two additional vertical positions for the seats and their occupants are provided, and the blocks are manipulated by rotating them independently on said screws, the seats being removable. 70

In position parallel with the carrier, spaced therefrom, underneath the same, and connecting the levers, there is hung at its terminals to swing with and between the levers on the transverse rod 31, the foot platform, which comprises the side bars 32, spaced apart and connected by a plurality of slats 33, and the beveled anti-pinch blocks 34, on its terminals. An upwardly and rearwardly swinging extension of this platform at each end thereof and projecting outwardly from the levers comprises two longitudinal bars 35, spaced apart and connected by the slats 36, and is mounted on the rod 31, between the bars 32 the bars 35, extend inwardly to effect an upward bearing against the adjacent slats of the platform to support the extension and the feet of the occupant of the seat. To the under edges of the bars 35, is secured the transverse foot or ladder rung 37, to be used in mounting and in dismounting from the swing. For this purpose the extension is turned up as in Fig. 2, and back against the platform. 90

To make the swing rigid in vertical position there is hung on the pivots 38, on the inner faces of the bars 32, the head terminals of the lock, which comprises the two bars 39, each having a hook recess 40, in its under edge at the foot terminal, and the connecting handle bar 41. In use the lock is swung forwardly to engage in the recesses the transverse rod 42, mounted on the adjacent levers at a suitable distance below the platform. 100

In position parallel with the carrier spaced therefrom, and above it, there is hung to swing on the pivots 43, on the outer faces of the levers the two guard rails, which comprise in each the thin longitudinal bar 44, having spacing blocks 45, secured to the inner faces of the terminals and having secured to the upper edge the stiffening bar 46. The said blocks obviate anti-pinch blocks. 110

On each of the transverse rods 31, carried by the levers and outside of the latter there is mounted to bear thereon at its head terminals a rolling brace or support, comprising a pair of bars 47, hung at their head terminals on said rod, having secured to the outer faces of their foot terminals the blocks 48, with the recess 49, formed in each, having the rollers 50, mounted in the recesses on the transverse bearings 51, spaced 120 130

apart and braced by the transverse bar 52, and carrying the spaced ladder rungs 53. To the inner face of the bar 52, there is secured centrally the screw eye 54, to which 5 is adjustably linked one end of the chain 55, which is linked at the opposite end to one end of the extension spring 56, the opposite end of which is linked to the screw eye 57, secured centrally to the board 7, of 10 the base. The link connecting the chain with the screw eye 54, has an open hook by means of which any desired link of the chain can be engaged to increase or to diminish the tension of the spring.

15 The arrangement and proportions appearing in Figs. 1 and 2, are specially designed for a house or nursery swing and not for adults. In use the lock is disengaged and a child mounts the swing by means of the 20 ladder rungs turning up and backward the extension of the platform using the rung 37, for the final step, the handle bar 16, being turned outward and upward to facilitate access to a seat. In operation the 25 child seizes one of the handle bars 13, which it faces, and presses it outwardly and downwardly. The stress of gravity in the act of mounting will cause considerable inclination of the swing forwardly as shown in broken lines in Fig. 1, indicating a portion thus inclined. Pressure on the handle and the 30 momentum increase the inclination in proportion to weight and the resistance of the spring under stress. The tendency of the 35 rolling supports is to yield entirely to the weight gradually falling thereon. The springs are mounted in such a manner as to yieldingly resist pressure to set limits of 40 adjustment by hooking the chain longer or shorter as desired. The top of the base automatically limits extreme oscillation. In reversing the movement, the handle bar is 45 pulled upward and backward the reaction of the spring greatly aiding the effort; and if there was momentum in the forward movement the spring will rebound with considerable force. When regular oscillation is 50 established there is added to the swinging sensation the sense of deep spring cushion reaction. It is to be noted that with the levers in vertical position they support the weight entirely, and that the occupants of the seats gradually fall under the influence of gravity, which gradually forces the rollers outward, and which tempers spring reaction.

55 The philosophy of the leverage is this: The foot terminals of the levers are fulcrumed on the bearing rods 3, on the base. The power is applied at or near the head terminals. The weight hangs intermediately on the pivots 18; hence, the levers are of "the second class." The weight of the operator drives him forwardly and downwardly 60 needing little or no lever power. To return

to central position he exerts lifting force on the handle bar bracing himself with his feet on the foot platform. He can lift to the extent that his weight bears on the seat. As neither carrier nor platform can yield, having bearings on the levers, the latter do yield turning on said bearings and the fulcrums. In reversing after backward movement the operator pushes the handles from him which are then close to his breast. In 70 this effort little bracing is required with feet, but the hands can apply more power than in the forward return. Lever action in pairs is alike either way. If the feet rest on the rolling brace in the modified seat arrangement hereinafter referred to, then said brace gives reaction to the feet. The structure shown is capable of oscillation to 50° or more in either direction. It is obvious that I combine the functions of standards or legs with those of levers in one integral part or member; and therefore, I 75 may use the terms interchangeably.

80 By slightly lifting the levers one pair at a time, the adjacent rolling brace can be rolled inward into alignment with the former and locked by the blocks or turns 58, pivoted on the inner edges of the bars 47, these bars including rollers are longer than the levers downward from the bearings 31; hence, the folding action described results in lifting the base from the floor as seen in Fig. 2, and contracts the swing to a limited space suitable for a house. This folding 85 automatically mounts the swing on rollers to move it elsewhere. Previous to folding the lock must be set to make the swing rigid.

90 With wide variations in weight in one or two children it is obvious that a single spring at each end of the swing will not 105 always be satisfactory. Therefore I have provided a relatively light spring 59, linked at one end to the screw eye 60, secured centrally and outwardly to one of the rungs 12, of each pair of the levers and linked at the 110 opposite end to the screw eye 61, secured centrally and inwardly to one of the rungs 53, on the adjacent rolling brace. The springs 56, and 59, with hooked connecting links can then be used, either one independently, or in combination, and thus I provide for 115 three degrees of ultimate resiliency.

120 The rolling braces meet the need of a longitudinally expanding and contracting base for use in a house, on a porch, or on any floor limited in space; but in constructing a swing for a lawn embodying the principles above shown I will use a longitudinally ample fixed base as it appears in Fig. 5. I provide a low supporting frame on which to mount the springs in lieu of the rolling supports or braces. To each of the sills 1, connected transversely by a plurality of rounds 4, are secured at their foot terminals the double braces 62, in two sets in 125 130

clined toward each other, connected at their head terminals by the longitudinal bar 63. The centers of the sills and the bars 63, are connected and embraced vertically by the 5 double bars 64, which are transversely and intermediately connected by the double brace bars 65, and carry at their head terminals the transverse eye bolts 66, and the parallel hook bolts 67. The levers 11, are fulcrumed 10 on the transverse rods 3, of the base and inside of the sills as shown in Fig. 6, and are connected longitudinally parallel with the base by the bars 66, which carry the transverse rod 69.

15 On each of the hook bolts 67, is hung the extension spring 56, being connected therewith by several links of the chain 55. With another section of the chain the spring is connected with the rod 69, at its terminal. 20 One link is shown detached and hung on each eye bolt. In practice the chain is to be hung permanently thereon as a safety measure. Adjustment of spring tension can then be effected by a plurality of chain links any 25 one of which can be hooked on the hook bolt. It is to be understood that the number of the coils in the spring is to be determined by the distance between the rod 69, and the hook bolt at the extreme limits of the oscillation of the rod when the swing is operated. 30 In such a swing I would provide a suitable number of rungs for mounting the levers as a ladder.

I do not limit myself to the use of extension springs. In Fig. 3, is shown a 35 double torsion spring, the coils 70, of which are mounted on one of the transverse rods 3, of the base, and the central upstanding double arms 71, of which offer a resilient 40 bearing for the rung 12, of the pair of levers fulcrumed on the same rod, in its intermittent engagement therewith. One of the two 45 terminal arms 72, of the spring appears in an end view Fig. 4, and is formed into an eye 73, at the end for embracing one of the rounds 4, of the base. Such a spring is 50 practical with a long base, one being thus mounted on each of the rods 3, is interposed to resist the action of gravity upon the carrier and the load thereon in its semi-oscillation 55 with respect to each spring. The arms 72, are mounted with respect to the winding of the coils of the spring. I may use this form of spring for primary use in the lawn structure, and connect the spring 56, as an auxiliary as the varying load may require.

I do not limit myself to the use of the seats described. If the carrier is removed it is evident that, if wide enough, any person 60 could use either end of the foot platform, minus the extensions, for a seat and utilize the rungs of the rolling brace (as many as needed) for foot supports. In such use the foot platform is converted into a combination seat and carrier, and I regard it as

the equivalent thereof in the claims herein-after set forth. Or, I may hang the platform in the same position relative to the handle bars as the carrier and still use the rungs of the rolling brace for foot rests. 70 Thus adapted my swing becomes available for use on a porch by adults with the occupants seated back to back; or, by contracting the swing longitudinally to one seat and expanding the swing in width or laterally, 75 I can provide room for several persons to be seated side by side as in the present type of porch swings. If in my porch swing I find it to be preferable for convenience of access to dispense with the handle bars, I 80 will round the head terminals of the forward levers as shown in Fig. 7, for use as handles.

It is also evident without the aid of drawings, that I can construct my swing contracted longitudinally and vertically to the limits of one seat for adults and to the space of a rocking chair, and thus constitute a chair swing for use in a house. In this form I would dispense with the portions of the rear legs or levers extending above the carrier or seat, add a suitable back to the seat, and retain the forward levers entire and with or without handle bars. 90

By contracting my swing suitably in all dimensions I can adapt it to a chair swing for a baby without altering the principles. Again, dispensing with the foot platform I may construct on the carrier a baby crib to serve as a crib swing in lieu of a rocking 100 cradle.

Be it known and understood that I contemplate the construction of my swing in the several forms specified and described, and modified to suit all possible places and purposes, all ages of persons, singular and plural in number. The ballast box and contents I will not require in all forms to offset the lifting tendency of the levers, but a portion thereof or a suitable substitute will be necessary for attaching the springs 56, or their connecting links with the screw eye 57. 105

Having thus described my invention I claim,—

1. In a non-suspension or vaulting swing, a framed base; a plurality of standards or legs carrying a plurality of transverse connecting members, and mounted to rock on the base; a carrier hung on and to swing with the legs, and forming a longitudinal connection for the latter; and manual means or members connected with the legs to swing the carrier to and fro and consisting of head extensions of the legs above the carrier. 115

2. In a non-suspension or vaulting swing, a supporting structure, a plurality of combination legs and levers connected transversely in pairs and fulcrumed to rock on the supporting structure, a carrier hung to swing on the combination legs and levers 120 125 130

intermediate to their terminals parallel with the supporting structure, anti-gravity springs mounted and interposed in such manner that the oscillation of the carrier 5 may be limited in amplitude, and hinge or pivot connections between the carrier and the combination legs and levers whereby moving and lifting power may be applied to said levers to swing the carrier to and 10 fro in a vaulting curve and in unstable equilibrium as set forth.

3. In a swing, integrally combined legs and levers connected transversely and rigidly in two pairs, fulcrumed at their foot 15 terminals to rock on a base, having their head terminals formed to serve as operating handles, having hung, to swing intermediate to their terminals, a carrier parallel to the base, and producing in action the 20 oscillation of the carrier in a vaulting curve.

4. In a swing having integrally combined legs and levers connected transversely and rigidly in two pairs, having their foot terminals fulcrumed to rock on a base, having 25 their head terminals formed to serve as operating handles, having hung, to swing intermediate to their terminals, a carrier parallel to the base, and producing in action the 30 oscillation of the carrier in a vaulting curve, the combination with said combined legs and levers, of springs mounted and interposed in such manner that the weight of the carrier and the load thereon may be sustained yieldingly and may provide spring 35 cushion sensations for the riders on the carrier as they travel to and fro in unstable equilibrium.

5. In a non-suspension or vaulting swing, a framed base; a plurality of legs connected 40 in pairs by ladder rungs, having integral head extensions or members connected by transverse handle bars, and mounted at their foot terminals to rock on the base; a framed carrier having a plurality of seats, hung on 45 and to swing with the legs intermediate to their terminals parallel with the base, and connecting longitudinally said pairs of legs; a framed foot platform hung at its terminals on the legs to swing parallel with and under 50 the carrier; a guard rail pivoted on said head extensions of the legs on each side of said seats and parallel with and above the carrier; and spring members mounted and interposed in such manner that the force of 55 gravity upon the carrier and the load thereon may be opposed and may be gradually overcome, when the carrier is rocked to and fro in unstable equilibrium.

6. In a non-suspension or vaulting swing,

a framed base; a plurality of legs having 60 their lower members connected in pairs by ladder rungs, having their upper members connected transversely by handle bars to propel the swing, and mounted at their foot terminals to rock on the base; a framed carrier having a plurality of seats, hung on and to swing with the legs intermediate to their terminals parallel with the base, and forming a longitudinal connection for the legs, a 65 foot platform hung at its terminals on the legs to swing parallel with and under the carrier; a rolling brace or support for each pair of legs and outwardly disposed, mounted at its head terminals on a transverse bearing carried by each pair of the legs intermediate to their terminals, and having its 70 foot terminals mounted on rollers; and a spring member or link connected with said brace and said base.

7. In a non-suspension or vaulting swing, 80 a framed base, having a pair of spaced transverse bearing rods or fulcrums, and built to include a ballast box; two pairs of combination legs and levers, connected by transverse rungs, fulcrumed to rock one pair 85 on each of said rods, and connected longitudinally intermediate to their terminals in a manner to swing by a carrier and by a foot platform; a rolling brace for each pair of said legs and levers outwardly disposed, comprising a pair of legs spaced apart by a bracing bar, carrying a plurality of ladder rungs, mounted at their head terminals on a transverse rod carried by each pair of legs and levers intermediate to their terminals, 90 and mounted at their foot terminals on rollers; and an extension spring member forming a link in a chain connecting the rolling 95 brace and the base.

8. In a non-suspension or vaulting swing 100 having a plurality of levers connected transversely in pairs, and fulcrumed to rock on a framed base, a carrier hung on and to swing with the levers intermediate to their terminals parallel with the base and effecting a longitudinal connection for the levers, comprising two spaced parallel bars connected by a pair of spaced transverse rungs, and a central transverse rod adapted to be engaged 105 by recesses or notches in the under rear edges of longitudinal seat members and in the like edges of the adjustable spacing blocks pivoted to and under said members, and carrying on said rod and on said rungs a pair of adjustable movable seats, substantially as described.

JOHN L. MARTIN.
